UNITED STATES PATENT OFFICE.

RUDOLPHE W. E. CHRISTESEN, OF NEW BRITAIN, CONNECTICUT, ASSIGNOR
TO THE RUSSELL & ERWIN MANUFACTURING COMPANY, OF SAME PLACE.

DESIGN FOR A DOOR-KNOB.

SPECIFICATION forming part of Design No. 21,769, dated August 9, 1892.

Application filed May 31, 1892. Serial No. 435,080. Term of patent 14 years.

To all whom it may concern:

Be it known that I, RUDOLPHE W. E. CHRISTESEN, a citizen of the United States, residing at New Britain, in the county of Hartford and 5 State of Connecticut, have invented and produced a new and original Design for a Door-Knob, of which the following is a specification, reference being had to the accompanying drawing, showing the same.

10 The only figure is a front elevation of a door-knob, showing my design.

The leading feature of my design consists in a central ring or rounding bead in ring form with radiating scrolls of a like rounded 15 form interlocked therewith.

1 designates a rounded bead in the form of a ring, and 2 designates rounded beads in

scroll form with their ends interlocked with said ring. Leaflets 3 are arranged as growing out from the branches between the scrolls. 20 A plain band 4 surrounds the knob at its greatest diameter, and toward the front of this is a raised ledge or border 5 in the form of conventional leaflets. The ground inclosed by this border, upon which the other ornaments appear, has any suitable surface. 25

What I claim is—

The design for a door-knob, as herein shown and described.

RUDOLPHE W. E. CHRISTESEN.
